WINDOW MOUNTED AIR CONDITIONING UNIT

Jack E. Wogoman, Dayton, Ohio, assignor to General Motors Corporation, Dayton, Ohio, a corporation of Delaware

Application September 5, 1952, Serial No. 21,338

Term of patent 7 years

(Cl. D62—4)

To all whom it may concern:

Be it known that I, Jack E. Wogoman, a citizen of the United States, residing at Dayton, in the county of Montgomery and State of Ohio, have invented a new, original, and ornamental Design for a Window Mounted Air Conditioning Unit, of which the following is a specification, reference being had to the accompanying drawing, forming a part thereof.

In the drawing:

Figure 1 is a perspective view of a window mounted air conditioning unit embodying my invention;

Figure 2 is a reduced top plan view; and

Figure 3 is a reduced side elevational view. The other side of the unit is like the side shown. The dominant features of my design reside in the portions shown in full lines.

I claim:

The ornamental design for a window mounted air conditioning unit, as shown and described.

JACK E. WOGOMAN.
